UNITED STATES PATENT OFFICE

2,463,960

TUBULAR LAMP BASE AND SOCKET

John H. Goehst, Chicago, Ill., assignor to Federal Enterprises, Inc., a corporation of New York

Application March 26, 1945, Serial No. 584,836

2 Claims. (Cl. 173—328)

1

This invention relates to lamp bases and sockets for tubular electric lamps of the double-ended discharge type. More particularly, this invention is concerned with lamps of this type provided with bases having a single outwardly projecting contact pin for lateral demountable engagement with a lamp socket.

This invention contemplates the provision of a lamp base and socket construction in which a circuit through the lamp is interrupted prior to removal of a lamp contact pin from its socket in order to prevent shock due to accidental contact with one of the contact pins during installation or removal of lamps.

A further object of this invention is to provide a lamp socket provided with a pair of flexible contact members arranged in spaced relation for lateral engagement by a single lamp contact pin, the contact pin serving to complete an electrical circuit between the flexible contact members during mounting of the lamp in a socket.

It is a further object of this invention to provide a lamp base and socket construction adapted to facilitate mounting or removal of lamps. In the mounting or removal of lamps provided with two or more contact pins on each end thereof, it is necessary to rotate the lamp to a predetermined position in order to align the several contact pins with their several socket slots, and as a result thereof the contact pins are often bent or broken. The use of a single contact pin thus facilitates replacement of lamps and also permits free rotational movement of the lamp to provide a better electrical contact surface between the contact pins and their respective socket contact members.

A further object of this invention resides in the provision of a lamp base and socket construction in which the several electrical contact members are adequately enclosed and protected to prevent contact with same to thereby eliminate the danger of shock or short circuits.

It is a further object of this invention to provide a socket holder having a tortuous passage terminating in a seat for a single contact pin, and a flexible contact member mounted within the socket holder to yieldably resist displacement of the lamp contact pin from said seat.

Another object of this invention is to provide a socket construction in which a terminal base is adapted to be detachably engaged between a socket holder and a mounting plate, the inner end of the terminal base being provided with means for supporting a pair of flexible contact members adapted to be laterally displaced upon mounting of a lamp contact pin in the socket holder.

Another object of this invention is to provide a lamp base and socket construction which is rel-

2

atively inexpensive to manufacture and which will not readily get out of order.

This invention embodies other novel features, details of construction and arrangement of parts which are hereinafter set forth in the specification and claims and illustrated in the accompanying drawing wherein:

Fig. 1 is a view partly in section and partly in side elevation showing a lamp base and socket embodying features of this invention.

Fig. 2 is a view of same partly in section and partly in front elevation.

Fig. 3 is a bottom plan view of the socket illustrated in Fig. 1.

Fig. 4 is a sectional view taken along the line 4—4 of Fig. 2.

Fig. 5 shows a wiring diagram illustrating a circuit for connecting a pair of tubular lamps with a source of power.

Referring now to the drawing for a better understanding of this invention, a double-ended gaseous discharge lamp 6 is shown as comprising an elongated tubular body portion 7 provided with a lamp base 8 at each end thereof. Each lamp base 8 is formed of insulating material and is provided with a single longitudinally extending contact pin 9 of tubular form.

The lamp socket is shown as comprising a holder 11 of insulating material and formed with a flange portion 12, a front wall 13, a back wall 14 and a side wall 16, said walls defining a chamber 17 to receive the inner end of the contact pin 9 and a pair of contact members 18 and 19. A baffle wall 21 is provided within the inner end of the chamber 17 and extending between the front wall 13 and the back wall 14. A tortuous slot 22 is formed in the holder and extends inwardly through the side wall 16 at 23 and thence around the end of baffle wall 21 to terminate in a contact seat 24 disposed on the opposite side of the baffle wall from the opening 23.

A terminal base 26 of insulating material is provided for detachable interlocking engagement with the flange 12 of the holder 11, and is formed with a contact supporting portion 27 projecting into the chamber 17. As more clearly illustrated in Fig. 2, the flexible contact members 18 and 19 are formed of flexible metallic strip material, preferably arranged in parallel alignment with the longitudinal axis of the socket holder, and adapted to have their free ends yieldably displaced laterally from their normal positions by mounting of a lamp contact pin. The flexible contact members are mounted in spaced relation upon the inner end of the terminal base portion 27 and secured thereto by means of terminal bolts 28 and 29 and nuts 30. The inner end or face of the terminal portion 27 is provided with a transverse rib 31 adapted to maintain the flexible contact members 18 and 19 in predetermined spaced position and also serves to hold the flexible

contact members against movement about the axis of their bolts 28 and 29.

The outer end of the terminal base is provided with a transversely extending rib 32 serving as a separating partition between the terminal bolts 28 and 29. The terminal base is also formed with four radially disposed arms 33 for detachable interlocking engagement between four corner posts 34 projecting outwardly from the flange 12 of the holder, as illustrated in Fig. 3, the outer surfaces of the arms 33 and corner posts 34 being flush on all sides to provide a smooth exterior appearance for the socket unit and a smooth surface engagement of the socket unit with a reflector plate 36. The terminal base 26 is also provided with a cylindrical portion 37 to project through an aperture 38 provided in the reflector plate 36.

The socket holder 14 and the terminal base 26 are adapted to be secured in assembled relation upon a reflector plate 36 or the like by means of a plurality of bolts 39 mounted in apertures 41 formed in and extending through the flange 12 and corner posts 34. After the holder 14 and terminal base 26 have been mounted in position on a reflector plate 36 by means of the bolts 39, the counter-bored ends 42 of the apertures 41 are adapted to be filled with a suitable insulating cement to cover the heads of the bolts 39 and thus eliminate any possibility of a short circuit between the contact members 9, 18 and 19 and the bolts 39.

In the use of a lamp base and socket construction of the type thus described, a pair of lamps 6 and socket contact members 18 and 19 of the several sockets may be connected in a circuit in the manner illustrated in Fig. 5 to eliminate any possibility of electrical shock due to accidental contact with a base contact pin 9 during installation or removal of a lamp in the circuit. In Fig. 5, a pair of lamps 6 are shown as arranged in a circuit connected to a source of electrical energy by a pair of leads 43 and 44. The lead 43 is connected to the primary side of a transformer 46, while the lead 44 is connected to a flexible contact member 19 of socket A. The contact member 18 of socket A is connected to a contact member 19 of a socket B, and the contact 18 of socket B is connected to the other side of the primary coil of the transformer 46. The opposite ends of the tubular lamps 6 are supported in sockets C and D which have one of their contact members, either 18 or 19, connected to the secondary coil of the transformer 46 by means of leads 47 and 48.

The socket construction and the circuit arrangements thus shown and described are particularly suitable for use with relatively low voltages and more particularly for use with a source of electrical energy of 110 volts, in which event the electrical energy transmitted through the leads 43 and 44 is changed, for example, to 600 volts by the transformer 46 to provide a sufficiently high current flow to pass through the gaseous discharge lamps 6. It will be noted that removal of the contact pin from the sockets A or B acts to break the circuit leading to the transformer 46, and thereby eliminates any possibility of a user being shocked due to contact with the disengaged contact pin. In the event a contact pin is first removed from the sockets C or D, the user will not be shocked by contact therewith as the 110 volt current transmitted by the leads 43 and 44 will not pass through the lamps 6.

In the use of the lamp base and socket of the type thus shown and described, it will be observed that the contact pin 9 may readily be mounted in operating position in the seat 24 of the slot 22, and that the lamp may be rotated if desired to provide a clean contacting engagement between the pin and the socket contact members. During mounting of a contact pin 9 it will be noted that the flexible contact members 18 and 19 are flexed rearwardly and act to yieldably resist displacement of the contact pin 9 from its seat 24 or from the inner end of the slot 22. It will also be noted that the partition 21 serves to prevent insertion of metallic objects into engagement with the contact members and thus eliminates the possibility of shock due to electrical contact therewith.

While this invention has been shown in but one form, it is obvious to those skilled in the art that it is not so limited but is susceptible of various changes and modifications without departing from the spirit and scope of the claimed invention.

I claim as my invention:

1. In a socket for use with a tubular fluorescent lamp having a base provided with a single contact pin, a lamp holder of insulating material, said lamp holder having a tortuous opening to receive a single contact pin when the latter is moved laterally, the walls of said opening terminating in a contact pin seat, and a pair of contact members electrically insulated from each other and secured within said holder to be laterally displaced in spaced engagement along one side of said contact pin to yieldably resist movement of said pin into or out of said contact pin seat.

2. In a socket for use with a tubular fluorescent lamp having a base provided with a single contact pin, a lamp holder of insulating material, said lamp holder having a tortuous opening to receive a single contact pin when the latter is moved laterally, the walls of said opening terminating in a contact pin seat, a pair of contact members electrically insulated from each other and secured within said holder to be laterally displaced in spaced engagement along one side of said contact pin to yieldably resist movement of said pin into or out of said contact pin seat, said lamp holder being formed with a baffle wall disposed between the entrance to said tortuous opening and said contact pin seat.

JOHN H. GOEHST.
